UNITED STATES PATENT OFFICE.

FRANKLIN L. HUNT AND KARL H. BEIJ, OF WASHINGTON, DISTRICT OF COLUMBIA.

AIRCRAFT SEXTANT.

Application filed June 3, 1921. Serial No. 474,582.

To all whom it may concern:

Be it known that we, FRANKLIN L. HUNT and KARL H. BEIJ, citizens of the United States, residing at Washington, District of Columbia, have invented certain new and useful Improvements in Aircraft Sextants, of which the following is a specification.

This invention relates to sextants particularly adapted for use on aircraft of all kinds. While particularly adapted for aircraft purposes, it will become apparent as the description proceeds that the sextant may be used on marine vessels and other places as well as on aircraft.

One of the main objects of the invention is to provide a hand instrument for the uses above indicated in which the parts are compactly arranged and assembled, the arrangement being productive of a light instrument which may be readily and quickly manipulated by hand for the purpose of taking observations either in the day time or at night time.

A further object of the invention is to provide means for compensating for temperature changes affecting the levelling bubble. It is desirable to have a levelling bubble of a certain size in order to provide for accurate observations and to that end we provide novel means for regulating the size of the bubble under varying temperatures.

A further object of the invention is to provide a novel construction and arrangement of supporting handle by which the sextant is held when in use, said handle being of hollow formation and containing a lamp energizing battery, resistance and a controlling rheostat therefor, the battery contact, contact springs, resistance and controlling means therefor being assembled on an end cap of the handle so that said parts may be withdrawn from the handle as a unit.

The invention also contemplates means for adjusting or setting the angle of the bubble mirror in primarily adjusting the instrument to give accurate readings; also means for adjusting the angle of the index mirror, with the same object in view.

With the above and other objects in view, the invention consists in the novel construction, combination and arrangement herein fully described, illustrated and claimed.

In the accompanying drawings—

Fig. 1 is a side elevation of the sextant; Fig. 2 is a vertical, longitudinal section

through the same looking in the opposite direction;

Fig. 3 is an end view thereof;

Fig. 4 is a longitudinal section through the handle, showing the parts contained therein;

Fig. 5 is an enlarged detail sectional view, showing the bubble adjusting or regulating means;

Fig. 6 is a diagram of the wiring and the parts affected thereby.

The sextant, which is designed to be supported by one hand and adjusted by the other, comprises, in the preferred embodiment thereof, oppositely arranged side plates 70 10 and 11 arranged in spaced relation to each other as shown in Fig. 3, sufficient space being left between said side plates to allow for the several elements hereinafter particularly referred to.

Between the side plates 10 and 11 there is mounted a sun glass 12, the same being supported by a binding screw 13 by means of which the angle of the sun glass 12 may be adjusted. Adjacent to the sun glass 12 is a semi-transparent index mirror 14 having trunnions 15 extending through the plates 10 and 11. One of the trunnions 15 has fast thereon a worm segment 16 which meshes with and is actuated by a worm 17. The shaft 18 of said worm extends downwardly and has a micrometer screw 19 thereon which is graduated as shown to enable the angle of the index mirror 14 to be accurately gaged.

The worm segment 16 is also graduated as 90 shown, for the same purpose, the graduations of the worm segment and the micrometer screw being read in conjunction with each other for the purpose stated. For use after dark, an electric lamp 20 is provided, the same being pivotally mounted at 21 on one of the side plates of the frame of the instrument and connected by flexible conductor 22 to a battery hereinafter described and arranged in a tubular handle 23 100 located at one side of the frame of the sextant and connected with such frame by struts 24.

Arranged within a short vertical extension 25 of the frame is a bubble lamp 26, the shank of which is screwed into a fitting 27 threaded into the extension 25. The fitting 27 has an exteriorly threaded reduced portion 28 which receives a cap 29. Below the bubble lamp 26 there is arranged a bubble

chamber 30 containing a suitable fluid or liquid by means of which a bubble 31 is formed in said chamber. At one side of the bubble chamber there is a diaphragm chamber 32 which is always in communication with the chamber 30 by means of a tubular connection or hollow screw 33 as best shown in Fig. 5. A flexible diaphragm 34 is placed in the chamber 32 in a medial position therein and clamped between rings 35 and 36, the outer side of the chamber 32 being closed by a cap 37 through the center of which is threaded an adjusting screw 38 that bears against the diaphragm 34 and enables the latter to be distorted. By the means just described, the amount of fluid or liquid in the chamber 30 may be changed or varied so as to regulate the size of the bubble 31, it being desirable to have a bubble of a certain size in order to render the readings more accurate. The bubble is used for the purpose of levelling the instrument simultaneously with sighting the sun during the day time or a planet or star at night.

Below the bubble chamber there is arranged an angularly disposed bubble mirror 39 which is supported within a cage 40 against springs 41, said bubble mirror 39 being adjustable by means of a plurality of adjusting screws 42 as shown in Fig. 2. This enables the angle of the bubble mirror to be accurately set for the purpose of reflecting the bubble into a collimating lens 43 which is situated between said bubble mirror and the index mirror 14 hereinabove referred to and the angle of which, as previously described, is adjustable by means of the micrometer screw 19. A flexible conductor 44 leads from the battery in the handle 23 to the bubble lamp 26.

The handle 23 is closed at one end by an end cap 45 having soldered thereto a contact spring 46 for the battery 47 contained in the handle. Cap 45 is detachable. The other end of the handle 23 is also normally closed by a detachable cap 48 and carries a central, threaded stem 49 having at its extremity a contact 50 which bears against the battery 47. The handle 23 carries a binding post 51 for the bubble lamp conductor 44 hereinabove described. Mounted upon and carried by the stem 49 is a resistance core 52 carrying a resistance element 53, along which is slidable the resistance control spring or contact 54 provided with an operating button 55. By this means more or less resistance may be thrown into the bubble lamp circuit for controlling the degree of illumination of said lamp, this being necessary in order that the brilliancy of the bubble may not interfere with accurate observations by throwing too great a glare into the eye of the observer. For energizing the bubble lamp we employ a bubble lamp push button 56 slidable through an opening in

the side of the handle 23 and adapted to contact with a spring terminal 57 screwed to a collar 58 on the stem 49 as shown in Fig. 4. It will now be seen that the resistance, battery contact, and the contact springs for the push buttons are all assembled on and supported by the end cap 48 so that when said cap is detached, all of said parts are removed therewith. This provides the necessary degree of accessibility to keep the parts just referred to in adjustment. Another push button switch 59 extending through the side wall of the handle 23 controls the lamp 20 above described. The wiring of the two lamps hereinabove described and the arrangement of the push button switches and resistance is illustrated in Fig. 6, enabling either or both of said lamps to be energized as needed and also enabling more or less resistance to be thrown into the bubble lamp circuit.

In operating the instrument in the day time, the eye is placed approximately at the position marked "A" in Fig. 2 so that the observer looks downwardly at an angle through the sun glass 12 and sees the sun reflected on the index mirror 14. Simultaneously he sees the bubble 31 which is reflected and projected by the lens against the index mirror 14. The two images of the bubble and the sun should coincide on the index mirror 14 before an accurate reading is obtained. They are brought into coincidence by a careful adjustment of the index mirror by means of the micrometer screw 19. At night time when sighting on a star, for example, the eye is placed under the index mirror, the observer looking upwardly through the index mirror 14 and directly at the star. The mirror 14 is then adjusted by means of the micrometer screw 19 until the bubble 31 is reflected and projected against the bottom of the index mirror so as to coincide with the image of the star as viewed through the index mirror. The instrument is particularly adapted for aircraft purposes as quick readings may be obtained in the manner above described although such use of the instrument is not limited to aircraft, the instrument being adapted for navigation purposes and, in fact, for any purpose where it is necessary to locate the position of a ship or vehicle of any kind. To further increase accurate readings the upper face of the glass or lens 60 which overlies the bubble chamber may be provided with concentric circles engraved or otherwise represented thereon for the purpose of more accurately centering the bubble 31. The bottom of the bubble chamber 30 is also composed of a wall or thickness of glass as shown at 61 or may consist of a lens forming a complementary part of the upper wall or lens 60 of the bubble chamber as shown in Fig. 5.

We claim:

In a hand sextant for aircraft, a frame, a sun glass, a levelling bubble, a bubble mirror, a bubble lens between the bubble and said mirror, an index mirror between the bubble mirror and the sun glass, a lens between the bubble mirror and the index mirror, a bubble lamp, a micrometer screw adjustment for the index mirror arranged at one side of the frame, a lamp for the last

named adjustment, a laterally arranged handle for the instrument arranged at the opposite side of the frame, and manually controlled means contained in said handle for energizing said lamps. 15

In testimony whereof we have affixed our signatures.

FRANKLIN L. HUNT.
KARL H. BEIJ.
